UNITED STATES PATENT OFFICE.

ABRAHAM BERNARD DIBNER, OF BROOKLYN, NEW YORK.

ELECTRICAL T CONNECTER.

Application filed June 17, 1925. Serial No. 37,753.

My invention relates to improvements in T connecters for electrical installations.

The present invention is a development of the T connector forming the subject matter of my co-pending application for Letters Patent of the United States, No. 703,143, filed March 31, 1924.

The invention comprises, briefly, two similar complementary members having hooked upper ends adapted to hook over the main horizontal conductor and depending body portions arranged to firmly grip and support the usual branch vertical conductors.

Unlike T connecters now in use, the present invention comprehends two exactly similar parts which may be assembled to provide an efficient form of connecting device for electrical installations of this character. It is therefore the principal object of the invention to produce a T connector which consists of two parts, similar in construction and interchangeable in installation.

A further object of the invention is to provide a T connector of this character, which may be manufactured at a greatly reduced cost. I accomplish this object by simplifying production, since only one type of casting is required in place of at least three used to produce T connecters of other types.

One embodiment of my invention is illustratively exemplified in the accompanying drawings, in which Figure 1 is a side elevational view of the improved T connector; Figure 2 is an end elevational view of the same; and Figure 3 is a transverse sectional view taken on the line 3-3 of Figure 2.

Referring to the drawings, 10 and 11 denote, respectively, the two complementary members, assembled to form the T connector, each member thereof having at its upper end a bent over or hook portion 12, which is substantially one half the overall width of the member, and which projects to a point 45° beyond the vertical center line of the main conductor A from which it receives its support. Depending from the hook portion 12 is a body portion which is provided with a semi-circular groove 13 disposed at right angles to the axis of the hook portion 12, and which is adapted to provide two contact surfaces about the branch conductor B, i. e., one surface for each member of the connector. Ears 14 projecting from the sides or ends of the body carry bolts 15 which, when tightened, grip the head portion of the T to the branch conductor B.

Unlike other types of T connecters, it is unnecessary for the branch conductor B to be shrunk fit or soldered to the connector, but simply clamped between the two members 10 and 11.

Both the hook portion 12 and the shorter adjacent half of each member are provided with tangentially disposed ears or lugs 16 which are parallel to the 45° radius determining the projection of the hook itself. Each ear 16 is provided with a bore 17 to receive a bolt 18 which clamps the hook portion of one member to the short half of the other member, as illustrated in Figure 2.

Depending from and integral with the head portion of each member is an arm 19 which serves the purpose of mechanically lengthening the point of support for the branch conductor B and which is provided with side projections 20 carrying bolts 21 cooperating with the projections of the other arm to establish a second point at which the T is clamped to the branch conductor, serving both mechanical and electrical objects.

Installation of the invention is as follows:

All the bolts being removed from each member, or half of the T connector, the hook portions 12 thereof are hooked over the main conductor A, so as to suspend the members by means of the hooks. The branch conductor B is then placed in one of the grooves 13 and the head of the other member moved into position so as to fix its groove 13 in contact with the opposite surface of conductor B. The conductor B is then in position corresponding to the contact surfaces provided in the two arms 19 for gripping it. The bolts 15, 18 and 21 are thereafter inserted and tightened. Electrical conductivity is thereby established between the main conductor A and the branch conductor B.

It will be clear that the use of clamping means instead of shrink fitting or soldering eliminates the necessity for the additional heating apparatus usually employed for this purpose. According to this invention, adjustment of the clamping means represents the final operation and no preliminary work is necessary and a complete operation of assembly may take place in one location and at one time.

Variations in sizes and conditions of tubing and cable conductors make no material difference when installations are made with the present T connector, because of the wide

adjustment possible and the amount of efficient electrical contacting surface between the parts.

For disassembling, the bolts of the connector need simply to be loosened and the latter is again available for use. This step is accomplished without the aid of heat for loosening a shrink fit or solder.

By providing a 45° overhang in the head 10 on each side of the main conductor A, it is possible for the connector to remain in full electrical contact with the main conductor by virtue of gravity and quite irrespective 15 of the grip imposed by the bolts. Similarly, the mechanical strains due to the weight of the suspended conductor B is transmitted mechanically directly to the main conductor A without having previously 20 to pass through the bolts 15 so that if these head bolts 15 were to be removed the connector would continue to function fully.

The conductors being placed outdoors are subject to vibrations caused by weather and electro-mechanical shocks imposed on such 25 electrical machinery. The vibrations set up in this manner have a tendency to concentrate the strains at points of fulcrum. Repeated strains beyond the elastic limit will cause crystallization of the conductor and 30 subsequent failure. To overcome this defect, means are provided, according to the present invention, whereby such strains will be distributed.

What I claim is:

1. A T connector for electric installations 35 comprising similar, interchangeable clamping members, each member having a body and a head portion provided with a hook projection extending beyond the vertical center line of said body for freely supporting said members in suspension from a conductor, each of said members having a depending portion adapted to embrace one half of a branch conductor and means for adjusting said members to clamp the latter about both conductors.

2. A T connector, as claimed in claim 1, in which the head member is provided with an integral I-shaped depending member having lateral projections and adjustable means 50 connecting said lateral projections.

3. A T connector, as claimed in claim 1, in which the depending member portions are fastened together at spaced points independently of the head portions of said members. 55

4. A T connector, as claimed in claim 1, in which the depending members are spaced from the branch conductors and provided with opposed, lateral projections embracing the said branch conductor in superposed, 60 clamping relation and fastening elements for said lateral projections.

In testimony whereof, I have signed my name to this specification, this 29 day of May, 1925.

ABRAHAM BERNARD DIBNER.
